UNITED STATES PATENT OFFICE.

DANIEL E. HENNESSY, OF HOLYOKE, MASSACHUSETTS, ASSIGNOR TO HERBERT W. COWAN, J. LEWIS WYCKOFF, AND EDWARD N. WHITE, AS TRUSTEES, DOING BUSINESS AS COWAN TRUCK COMPANY.

TRUCK.

1,311,165.

Specification of Letters Patent. Patented July 29, 1919.

Application filed October 4, 1915. Serial No. 53,897.

To all whom it may concern:

Be it known that I, DANIEL E. HENNESSY, a citizen of the United States, residing at Holyoke, Massachusetts, have invented certain new and useful Improvements in Trucks, of which the following is a clear, full, and exact description.

This invention relates to machines for lifting and transporting goods, and is herein shown as embodied in a machine which is especially intended for use in transporting goods to and from and forming them into or removing them from tiers, as in warehouses where it is desirable to store goods as compactly as possible. It will be understood, however, that the invention is not restricted to the illustrated embodiment or to the illustrated use, but that it is of general applicability in the art to which it relates.

An object of the invention is to provide a machine which will do away with substantially all arduous manual labor in handling goods, which are, or are to be, piled in tiers.

The invention aims also to provide an improved system of handling goods which will not only facilitate their handling but will also reduce to a minimum the labor involved and the cost, as well as the wear and tear on the goods.

A further object of the invention is to provide an elevating truck in which the elevating mechanism may be relieved entirely of any strains incident to the movement of the load over rough places.

An important feature of the invention is the provision of load lifting and depositing arms coöoperating with removable platforms which remain in and form a part of the tier, the novel construction of the removable platform constituting a further important feature of the invention.

Other objects and important features of the invention will appear from the following description and claims when considered in connection with the accompanying drawings, in which—

Figure 1 is a side elevation of a combined truck and tiering machine, embodying the present invention;

Fig. 2 is a sectional detail on the line 2—2 of Fig. 1;

Fig. 3 is a sectional detail on the line 3—3 of Fig. 2;

Fig. 4 is a plan view of the machine;

Fig. 5 is a detail view showing one of the 55 steering knuckles and the universal joint connection to the driving wheel;

Fig. 6 is a detail view showing the arrangement of the steering shaft with respect to the driving mechanism; 60

Fig. 7 is an elevation looking from the rear;

Fig. 8 is a sectional detail showing the arrangement of the screws by which the elevation of the load is effected; 65

Fig. 9 is a sectional detail of the vertical guides, on the line 9—9, Fig. 7;

Figs. 10 and 11 show two adjacent tiers with the truck in position to operate on one of the tiers; 70

Fig. 12 is a rear elevation illustrating the operation of the truck when placing goods on top of a partly formed tier;

Fig. 13 is a side elevation illustrating substantially the same operation as that 75 shown in Fig. 12;

Fig. 14 is a sectional detail illustrating the relative positions of the load-lifting arms, the removable platform, and the load-carrying frame of the truck. 80

The machine herein shown and which embodies the invention in a preferred form, is intended to be used in connection with skids and removable platforms, the platforms being left in the tier of goods formed by the 85 aid of a machine, and in order that the machine may be moved into such relation to the tier that it may deposit the removable platform with its load of goods upon the tier and yet itself occupy as little space 90 as possible in the storage room or other place in which the tier is to be formed, the machine is preferably so constructed that a part thereof passes between the skids upon which the tier is supported and beneath the 95 tier, whereby it brings another part into position over the tier.

As hereinabove suggested, the machine comprises a truck and an elevating mechanism, the illustrated truck comprising a 100 horizontal load-supporting frame 2, of generally U-shaped form, having supporting

wheels 4 mounted upon an axle 6, said frame at its rear end being connected to a second frame 8 in which are mounted the various mechanisms for operating both the truck 5 and the elevating mechanism. Driving wheels 10 coöperate with the wheels 4 in supporting the truck, and are connected to power-operated means, comprising an electric motor 12, whereby the truck may be 10 moved by power from one place to another. The load-carrying frame 2 has its upper load-receiving surface at such a distance above the floor that this surface will be below the tops of the skids 14 with which the 15 truck is intended to be used, whereby this part of the truck may pass between these skids when one of the removable platforms 16 or any other body is resting upon said skids. This part of the truck is also relatively 20 narrow with respect to the other parts of the truck to facilitate its passage between these skids.

The elevating mechanism or tiering mechanism comprises arms 18 attached to 25 vertically movable guides 20, connected to a cross-piece 22, through which the power of the elevating mechanism is transmitted to said guides and arms. The arms 18 (see Figs. 3 and 14) comprise relatively deep or 30 wide vertical webs 24 and inwardly projecting flanges 26, formed, as shown, of angle irons, attached to the inner faces of the webs 24 so that the flanges 26 will be flush with the upper edges of said webs, said 35 webs 24 being relatively thin so that they can pass between tiers which are comparatively close together. The arms 18 are free at their rear or outer ends, and to stiffen them against lateral movement, triangular 40 webs or gusset pieces 28 are connected to the arms and to brackets upon the guide members 20, which brackets may consist of pieces of angle iron extending at right angles to the angle irons which form the flanges 26. 45 The arms 18 are adapted to cooperate with a removable platform 16 like that hereinabove referred to, which platform is shown rabbeted at its lateral edges, and is of such width that the rabbeted portions 50 thereof will rest upon the flanges 26 of the arms 18, the platform being preferably slightly narrower than the space between the webs 24. The parts of the platform 16 which engage the flanges 26 are preferably 55 protected and reinforced by angles 30 which cover the undersurface of the rabbet and the edge of the platform. The rabbet is preferably deeper than the thickness of the flange 26, whereby vertical movement of the 60 arms 18 to bring the flanges out of engagement with the platform 16 may take place even when said flanges 26 project over some object upon which the platform rests.

The illustrated elevating mechanism 65 comprises a series of telescoping threaded cylin-

ders, the outermost cylinder 32 being rigidly connected to the cross-piece 22 and having a few internal threads 34 at its lower end which engage the external threads of the second cylinder 36, which likewise is internally 70 threaded at its lower end 38 to co-operate with the external threads of the third cylinder 40 which has internal threads at 42 co-operating with the threads of a screw 44 connected to turn with a bevel 75 pinion 46 having its bearing upon a stationary cross-piece 48 between two vertical stationary guides 50 rigid with the truck frame.

Meshing with the bevel pinion 46 is a second bevel pinion 52 driven from an electric motor 54, mounted in the frame 8 below a platform 56, upon which the operator of the truck stands. The guides 20 to which the arms 18 are attached, are preferably of such height that when in their lowermost 80 position, the truck may be run through any door through which it is usual to go in transferring goods of the kind with which the truck is intended to be used, such, for example, as the door of an ordinary freight 85 car, and in order that the arms 18 may be elevated to a sufficient height to deposit their load upon the top of the storage tier, intermediate telescoping guides 58, 60 and 62 are provided between the inner stationary 90 guide 64 and the outer movable guide 20, there being preferably the same number of telescoping guides as there are telescoping screws. To insure the movement of one or 95 more of the intermediate guides before the outer guide 20 has reached the point where it would not be properly supported against lateral strain, the guides may be interconnected in any suitable manner, as for example, by pin-and-slot connections 66 and 100 68, the slots 68 being long enough to allow considerable relative movement of the guides but preventing relative movement beyond a point where sufficient bearing surface would not be provided to sustain the 105 telescopic support in substantially vertical position against the tendency of the load carried upon the arms 18 to bend it to one side. The guides 20, 58, 60 and 62 may be formed in any suitable manner as for example from channel iron of the proper dimensions, but as herein shown, they are formed of angle iron strips connected by cross-pieces 70.

From an inspection of Fig. 1 of the drawings, it will be noted that the arms 18 may be lowered to bring their load-carrying surfaces into or below the plane of the load-carrying surface of the truck frame 2, and that when thus lowered, a clear substantially 110 rectangular space is provided between the frame 2 and the elevating mechanism. Although this part of the truck is at times moving ahead of the other part, inasmuch as the steering of the truck is done from 115

the other end, for convenience the load part of the truck will be called the rear end of the truck and the part of the truck comprising the frame 8 will be called the forward end of the truck.

In order to brace the elevating mechanism against the lateral strains incident to the lifting of the load upon the projecting arms 18, the frame 8 comprises oblique braces 72 connected to the vertical frame member 74, and the load lifted by the arms 18 is counter-balanced by the weight of the motors 12 and 54 mounted in the frame 8 and by the weight of the storage batteries 76 also carried by the frame 8 in front of the vertical frame member 74.

In order that the truck may be steered as well as power-driven, the driving wheels 10 are preferably mounted on steering knuckles 78, a short shaft 80 for each wheel 10 being connected by a universal joint 82 to one-half 84 of a driving shaft, which is connected to the other half of said driving shaft by any suitable differential gearing driven from the motor 12 through a pinion 86 connected to one end of a sleeve 88, mounted in a bearing 90, the other end of said sleeve carrying the pinion 92 connected to the differential gearing. The steering knuckles 78 have arms 94 connected by links 96 to an arm 98 upon the lower end of a steering shaft 100 which is connected by gears 102 to another shaft 104 in a steering post 106, mounted upon the platform 56, said shaft 104 being driven by bevel gearing in the head 108 of said steering post from a star wheel 110. It will be noted that the driving and steering wheels 10 of the truck herein shown are located at a greater distance apart than the supporting wheels 4, see Fig. 4. This is the preferred construction when the truck is to be used in working along the front of a row of piles or tiers in which the skids are arranged transversely to the row. If, however, it is desired to work lengthwise of relatively long skids fixed to the floor, it is preferable that the steering and guiding wheels 10 be located so that they may pass between the skids, although of course they might be arranged to pass outside of the skids if this would not interfere with placing adjacent rows of piles in the desired proximity.

The motor 12 which drives the truck may be controlled in any suitable manner, as for example from a switch box 112 having a switch operating handle 114, and the motor 54 which operates the elevating mechanism, may be controlled from another switch box 116 having a switch operating handle 118.

The operation and method of use of the illustrated truck and tiering machine is as follows: If the goods to be transferred are not already piled upon platforms of the type of the platform 16 herein shown, one of these platforms will preferably be placed upon a

pair of skids 14 of the proper height and so spaced that the rear or load-carrying end of the truck can pass between them and then the goods to be transferred and piled in tiers will be piled upon the platform 16. These 70 goods may be piled flush with the edges of the platform, as shown in Figs. 10 and 11. The desired quantity of goods having been piled upon the platform 16, the truck is run between the skids with its load-lifting arms 75 18 in the position shown in Figs. 1, 3 and 7, thus bringing the flanges 26 of these arms beneath the rabbeted edges of the platform 16. The elevating mechanism is then actuated and the arms raised until the flanges 26 80 engage the platform 16 and lift the platform from the skids 14. The truck is then backed out from between the skids 14, and if it is to be run over a rough surface, the arms 18 are preferably lowered until the platform 16 85 is deposited upon the load-carrying frame 2 of the truck, thus relieving the elevating mechanism of the strain of the load while the load is being transported from one place to another. 90

The load of goods is now carried to the place where the goods are to be stored or piled, at which place skids similar in their transverse dimensions to those used in loading will be located. If the load of goods is 95 the first to be deposited upon these skids, the elevating mechanism will be operated sufficiently to cause the arms to lift the platform 16 high enough so that it will pass over the upper edges of these skids as the truck is 100 run between them. The arms will then again be lowered, as shown in Fig. 1, to deposit the platform 16 upon the skids when the truck can be withdrawn, leaving the platform 16 with its load of goods upon the 105 skids 14.

The truck is now again loaded in the manner above described and again brought to the place where the tier is being formed. In order to place the next load in position, the 110 elevating mechanism must be operated sufficiently to cause the arms 8 to lift the platform 16 above the upper surface of the pile of goods 120 which constituted the first load, when the truck can be run between the skids 115 14 again, thus bringing the platform 16 over the top of the goods 120, with the webs 24 of the arms 18 embracing the pile of goods or tier 120, and the flanges 26 projecting over the upper surface. The elevating mechanism is now actuated to lower the arms 18, 120 thus depositing the platform 16 on the pile 120, the lowering operation being continued until the flanges 26 are moved out of engagement with the under faces of the rabbets in the platform 16, sufficient space being provided between these faces and the upper surface of the pile 120 for this purpose. The truck can now again be withdrawn and run to receive another load which can be elevated 125 130

into position to be deposited upon the pile 122 in the same manner that the pile 122 has been deposited upon the pile 120. This tiering operation can be continued until the 5 limit of extensibility of the telescoping support of the truck is reached.

What I claim as new is:—

1. In a combined truck and tiering machine, a truck body, elevating mechanism 10 mounted on said body, and an elevating support connected at one end to said elevating mechanism and comprising load-carrying arms arranged to carry their load above the truck body and having their load-supporting parts lying outside the sides of said body and unconnected above said body, whereby said arms may embrace and deposit their load upon a tier between the 15 planes of the sides of which said truck body can enter.

2. In a combined truck and tiering machine, a truck body, elevating mechanism mounted on said body, and an elevating support connected at one end to said elevating mechanism and comprising load-carrying arms arranged to carry their load above the truck body and having their load-supporting parts lying outside the sides of said body and unconnected above said body, 25 whereby said arms may embrace and deposit their load upon a tier between the planes of the sides of which said truck body can enter, said arms having load-supporting portions inwardly directed and arranged to project over said tier.

3. In a machine of the class described, a truck base and elevating means mounted upon said base, said means comprising a removable platform and platform supporting 40 arms lying outside opposite sides of said truck base and movable into platform-depositing relation to said base.

4. In a machine of the class described, a truck base and elevating means mounted 45 upon said base, said means comprising a removable platform and platform supporting arms connected at one end only, lying outside opposite sides of said truck base and movable into platform-depositing relation to said base.

5. In a machine of the class described, a truck having a body and supporting wheels, elevating mechanism mounted on said truck body, and an elevating support comprising 55 a pair of arms connected to said mechanism at one end and arranged to embrace said truck body when in lowered position.

6. In a combined truck and tiering machine, a truck, and elevating means mounted 60 on said truck, comprising a removable platform and platform-supporting arms connected at one end only and spaced to engage said platform beneath its lateral edges and to embrace said truck when in lowered 65 position.

7. In a combined truck and tiering machine, a truck, and elevating means mounted upon said truck, comprising a removable platform having lateral rabbets and platform-supporting arms arranged to engage 70 said platform in said rabbets and to embrace said truck when in lowered position.

8. In a machine of the class described, a truck base and elevating means mounted upon said base, said means comprising a removable platform having lateral rabbets and platform-supporting arms connected at one end only and having inwardly projecting rabbet-engaging flanges of a thickness less than the depth of said rabbets, said arms 75 80 lying outside opposite sides of said truck base.

9. In a machine of the class described, a truck, elevating mechanism mounted on said truck, an elevating support connected to 85 said mechanism, comprising a pair of parallel arms having vertical webs and horizontal supporting portions, and a removable platform having lateral rabbets arranged to receive the horizontal portions of said arms, 90 said rabbets being of a depth greater than the thickness of said horizontal portions and said arms being arranged to embrace said truck when in lowered position.

10. A machine of the class described comprising, in combination, a truck having a load supporting frame, load lifting mechanism mounted on said truck and comprising a pair of arms spaced to embrace said frame when in lowered position and arranged to be 100 lowered to bring their load supporting surfaces into the plane of the load supporting surface of said frame, and a removable platform co-operating with said arms and having locating shoulders arranged to prevent 105 movement of said platform transversely to said arms but permitting movement thereof lengthwise of said arms.

11. In a machine of the class described, a truck, elevating mechanism mounted on said truck, an elevating support connected to said 110 mechanism and comprising parallel spaced arms connected only at one end and having downwardly projecting vertical stiffening portions and inwardly-directed, horizontal 115 load-supporting portions, whereby said stiffening portions may embrace a tier of goods over which said horizontal portions project.

12. A machine of the class described comprising, in combination, a truck having a 120 load supporting frame, and lifting mechanism mounted on said truck and comprising arms having deep vertical webs and inwardly projecting horizontal flanges, said arms being arranged to be lowered into embracing relation to said frame and to bring 125 their flanges into the plane of the load supporting surface of said frame, and a removable platform having its edges rabbeted to receive the flanges of said arms.

13. A machine of the class described having, in combination, a truck and load lifting means mounted on said truck, said means comprising a jack and spaced load supporting arms connected to said jack and having the space between their load engaging parts wholly unobstructed, said truck having a load supporting frame opposed to the free space between said arms, and said frame and said arms being relatively movable into and out of load transferring relation to each other.
14. A machine of the class described having, in combination, a truck, load lifting means mounted on said truck and comprising a jack and spaced load supporting arms connected to said jack and having the space between their load engaging parts wholly unobstructed, and a removable platform carried by said arms, said truck having a load supporting frame opposed to the free space between said arms, and said frame and said arms being relatively movable into and out of platform transferring relation to each other.
15. A machine of the class described comprising, in combination, a truck having a load supporting frame, load lifting means mounted on said truck and comprising arms arranged to be lowered into embracing relation to said frame and to bring their supporting surfaces into the plane of the load supporting surface of said frame, and a removable platform carried by said arms and having a portion thereof projecting below the load supporting surface of said arms, whereby said platform is deposited upon said frame when said arms are moved to bring their supporting surfaces into the plane of the supporting surface of said frame.
16. A machine of the class described comprising, in combination, a truck having a load supporting frame, load lifting means mounted on said truck and comprising a support arranged to be lowered to bring its load supporting surface into the plane of the load supporting surface of said frame, and a removable platform carried by said support and having a portion projecting below the load supporting surface of said support and located above the load supporting surface of said frame.
17. In a combined truck and tiering machine, a truck body, elevating mechanism mounted on said body, an elevating support connected at one end to said elevating mechanism and comprising load-carrying arms arranged to carry their load above the truck body and spaced to provide a clear space above said body overlapping the sides thereof, whereby said arms may embrace a tier between the planes of the sides of which said truck body can enter, and a removable plat-
- form carried by said arms, said arms having inwardly directed flanges of a thickness less than the thickness of the removable platform, and said platform having flange engaging faces so located as to allow vertical movement of said arms to disengage them from the platform when said platform has been deposited upon the tier.
18. In a combined truck and tiering machine, a truck body; elevating mechanism mounted on said body, an elevating support connected at one end to said elevating mechanism and comprising load-carrying arms arranged to carry their load above the truck body and spaced to provide a clear space above said body overlapping the sides thereof, whereby said arms may embrace a tier between the planes of the sides of which said truck body can enter, and a removable platform carried by said arms, said removable platform having arm and tier engaging surfaces at different levels and the thickness of the platform-engaging parts of said arms being less than the vertical distance between said levels.
19. In a combined truck and tiering machine, a truck having a load supporting part, elevating mechanism mounted upon said truck, an elevating support connected to said elevating mechanism and comprising a pair of arms projecting laterally and independently therefrom, and a removable platform, said arms having vertical webs spaced apart a greater distance than the width of said platform and having inwardly extending platform supporting portions, the load supporting part of said truck lying beneath the free space between said arms and said arms being movable into platform depositing relation to said load supporting portion.
20. A combined truck and tiering machine for use in forming a tier of goods in connection with a pair of skids upon which said tier is supported and with removable platforms left in the tier, comprising, in combination, a truck adapted to pass between said skids and beneath said tier, elevating mechanism mounted on said truck at a point remote from one end thereof, an elevating support connected at one end to said elevating mechanism and projecting substantially horizontally therefrom in the direction of the aforementioned end of the truck, a removable platform carried by said support, said platform having upon its under side tier and support engaging surfaces at different levels, and said support having its platform engaging part of less thickness than the vertical distance between said levels and being movable into platform-depositing relation either to said skids or to a tier supported upon said skids when said truck is between said skids.

21. A combined truck and tiering machine for use in forming a tier of goods in connection with a pair of skids upon which said tier is supported and with removable platform 5 forms left in the tier, comprising, in combination, a truck adapted to pass between said skids and beneath said tier, elevating mechanism mounted on said truck at a point remote from one end thereof, said truck from 10 said end to said elevating mechanism being of less height than said skids, platform supporting arms connected at one end to said elevating mechanism and projecting substantially horizontally therefrom in the direction of the aforementioned end of the 15 truck, a removable platform carried between said arms, said platform having tier and arm engaging surfaces at different levels and said arms having their platform engaging parts 20 of less thickness than the vertical distance between said levels and being movable by said mechanism into platform-depositing relation either to said skids or to a tier supported upon said skids when said truck is 25 between said skids.

22. In combination, a truck having a load supporting frame, elevating mechanism mounted on said truck, and an elevating support comprising platform supporting arms 30 and a removable platform, said arms being connected at one end to said mechanism and arranged to support the platform over said load supporting frame, and said platform 35 and said frame having opposed parts between said arms arranged to coöperate to support the load when said arms are moved into their lowered position.

23. In combination, a truck having a load 40 supporting frame, elevating mechanism mounted on said truck, and an elevating support comprising platform supporting arms and a removable platform, said arms being connected at one end to said mechanism and being arranged to engage said platform beneath its edges only and to support said 45 platform over said load supporting frame, opposed parts of said platform and said frame between said arms being arranged 50 to coöperate to support the load when said arms are moved into their lowered position.

24. In a machine of the class described, a truck, elevating mechanism mounted on said truck, parallel supporting arms connected 55 at one end to said mechanism and having inwardly directed flanges, and a removable platform supported wholly by said flanges and within the sides of said arms the space between the platform supporting flanges being entirely unobstructed and said arms being arranged to support said platform over 60 said truck.

25. In a machine of the class described, a truck, elevating mechanism mounted on said 65 truck, an elevating support connected to said

mechanism and comprising parallel spaced arms having inwardly directed flanges, and a removable platform having two of its opposite side edges resting upon said flanges and wholly supported thereby, said edges being rabbeted to a depth greater than the thickness of said flanges, said arms being arranged to carry said platform above said truck and being movable into platform depositing relation to said truck. 70 75

26. In a machine of the class described, a truck having supporting wheels and a body having a substantially horizontal upper surface, elevating mechanism mounted on said truck, an elevating support connected to said mechanism and comprising a pair of arms spaced apart a distance greater than the width of said truck body and so connected to said mechanism that they may 80 be lowered to bring their upper edges into the plane of the upper surface of said truck. 85

27. In a combined truck and tiering machine, a wheeled base, elevating mechanism mounted on said base and comprising parallel spaced horizontal arms supported and connected at one end only, said arms, having inwardly projecting load supporting flanges, a removable platform adapted to be carried by said flanges between said arms, said platform having flange and tier engaging surfaces at different levels vertically spaced a distance greater than the thickness of said flanges. 90 95

28. A machine of the class described comprising, in combination, a truck having a load supporting frame, and load lifting means mounted on said truck and comprising a pair of arms arranged to be lowered into embracing relation to the load carrying 100 frame and to bring their load supporting surfaces into the plane of the load supporting surface of said frame. 105

29. A machine of the class described comprising, in combination, a truck having a load supporting frame, load lifting means mounted on said truck and comprising a pair of arms arranged to be lowered to bring their load supporting surfaces into the plane of the load supporting surface of said frame 110 115 and so spaced that they embrace said frame and are also separated from the sides thereof to permit the entrance between said arms and said frame of load supporting skids.

30. A machine of the class described comprising in combination, a truck having a load supporting frame, load lifting means mounted on said truck and comprising a pair of arms arranged to be lowered into embracing relation to said frame and to bring their 120 load supporting surfaces into the plane of the load supporting surface of said frame, and a removable platform constructed and arranged to be engaged at its edges by said arms. 125 130

31. In a machine of the class described, a truck body having a substantially horizontal upper surface, elevating mechanism mounted on said truck body, an elevating support 5 connected to said mechanism and comprising arms extending parallel to each other and to said upper surface of said truck body, said arms being spaced apart sufficiently to embrace said truck body when 10 brought into their lowermost position, each arm being also so spaced laterally from the adjacent edge of said truck body, when in its lowermost position, as to permit the introduction of load supporting skids between 15 said arms and said truck body.
32. A machine of the class described having, in combination a wheeled base, vertically operating elevating means mounted upon said base and comprising parallel horizontal arms having inwardly projecting load supporting flanges lying outside opposite sides of said base, a removable platform carried by said flanges between said arms, said base and said arms being relatively movable by the operation of said mechanism to bring said arms into platform depositing relation to said base.
33. In a machine of the class described, a truck, elevating mechanism mounted upon 30 said truck, and an elevating support connected to said mechanism and comprising a pair of arms arranged to embrace the truck when in lowered position, said arms having vertical stiffening webs and inwardly 35 projecting load-supporting flanges.
34. In a machine of the class described, a truck, means for driving said truck, elevating mechanism mounted on said truck, an elevating support connected at one end to 40 said elevating mechanism, power-operated means for effecting the elevation of said support through said mechanism, said power-operated means and said mechanism being located near one end of said truck and said 45 support straddling and being arranged to carry its load above the other end of said truck.
35. In a machine of the class described, a truck having a body and supporting and
- driving wheels, power-operated means for 50 driving said truck, elevating mechanism mounted upon said truck, an elevating support connected at one end to said mechanism, said power-operated means, said mechanism and said driving wheels being located near one end of the truck and said support straddling and being arranged to carry its load above the other end of said truck. 55
36. A machine of the class described comprising, in combination, a truck having a load supporting frame, and load lifting means mounted on said truck and comprising arms arranged to embrace said frame when in lowered position and vertical telescoping guides, each arm being connected at one end to one of said guides. 60
37. A machine of the class described comprising, in combination, a truck, load lifting means mounted on said truck and comprising a vertically arranged jack, vertical guides upon opposite sides of said jack, load supporting arms spaced to embrace said truck when in lowered position, and arm carrying members connected to said jack 70 and guided by said vertical guides. 75
38. A machine of the class described comprising, in combination, a truck having a load supporting frame and supporting and driving wheels, load lifting means mounted 80 on said truck and comprising a pair of arms arranged to be lowered into embracing relation to the load carrying frame and to bring their load supporting surfaces into the plane of the load supporting surface 85 of said frame, said driving wheels being upon the side of said lifting means remote from said arms, and power actuated means, also located upon the side of said lifting means remote from said arms, for driving 90 said wheels and for operating said lifting means.

Signed at Holyoke, Mass., this 1st day of October, 1915.

DANIEL E. HENNESSY.
